ATTORNEYS

UNITED STATES PATENT OFFICE.

LEONARD FOOTE, OF PEDRO MIGUEL, CANAL ZONE, PANAMA.

GAUGE.

Application filed November 2, 1921. Serial No. 512,286.

To all whom it may concern:

Be it known that I, LEONARD Foote, a citizen of the United States, and a resident of Pedro Miguel, Canal Zone, Panama, have invented a new and Improved Gauge, of which the following is a full, clear, and exact description.

This invention relates to improvements in gauges, particularly to a water gauge adapted to indicate whether or not the water in an automobile radiator has fallen below a predetermined level.

An object of the invention is to provide a gauge of this character, which will enable the driver of a car to ascertain approximately the amount of water in the radiator without removing the radiator cap.

A still further object is to provide a device of this character, which will be simple and practical in construction, neat and attractive in appearance, durable and efficient in use, and comparatively inexpensive to manufacture.

With these and other objects in view, the invention consists in certain novel features of construction and combinations and arrangements of parts, as will be more fully hereinafter described and pointed out in the claims.

30 In the accompanying drawings:—

Figure 1 is a view partly in elevation, but mainly in longitudinal section through my improved gauge;

Figure 2 is a similar view illustrating a slight modification; and

Figure 3 is a fragmentary view in side elevation of the indicating tube.

Referring specifically to Figure 1 of the drawings, 1 represents a radiator having the usual threaded spout 2, and 3 represents a threaded cap fitting within the spout. A circular frame 4 supports a circular plate 5. The lower end of the frame is formed with a depending threaded nipple 6 which extends through an opening 7 in the radiator cap 3.

Integral with the top of the frame 4 is an additional frame 8, which accommodates and supports a rubber bulb 9. A glass tube 10 extending through the nipple 7 and frame 4 and into the lower end of the frame 8 communicates with the bulb 9. The lower end of the glass tube extends into the radiator for a predetermined distance. A protecting sleeve such as 11 may be screwed onto the lower end of the nipple 7 around the

tube 10 and serves as a nut to hold the parts in proper relationship. The frame 8 is provided with an opening such as 12, so that an operator may use his fingers to compress the bulb 9 and suck water into the tube 10. Although it is not shown, the exposed portion of the tube might be protected by a crystal mounted on the frame 4.

The tube 10 or the plate behind the tube is preferably marked in some way to accentuate the rise of water therein when the bulb 9 has been squeezed and released. For instance, in Figure 3 I have shown the caption "Full" displayed in narrow letters back of the tube. When the water rises in the tube, these letters will be greatly magnified in breadth and accentuated.

In Figure 2, I have illustrated a slight modification wherein a metal tube 13 is passed through an opening 14 in the radiator cap 15. The tube at its upper end opens into a bulb 16. The tube at its lower end is considerably reduced, as indicated at 17 and includes a screw threaded portion 18 so that a nut 19 may be utilized to hold the tube against movement within the cap.

The operation of the device illustrated in Figure 1 is as follows:—

In applying the gauge, it is first necessary to determine just how low the water in the radiator may become without approaching the danger mark. The length of the tube in each instance depends upon just where the danger mark in the particular radiator is located and the end of the tube 10 is located slightly above the danger mark. When the operator squeezes and releases the bulb 9 and water rushes into the tube 10, he will know that he is in no immediate danger of running out of water. If, however, when the bulb 9 is squeezed and released, the operator fails to raise water in the tube, he will know immediately that more water should be introduced into the radiator. The bulb 9 may have a very small perforation therein so that after the water has been raised, it will drain back into the radiator. This, however, is not essential since if the water remains in the tube 10 and the water in the radiator falls below the predetermined level, when the operator again squeezes the bulb 9 and expels the water from the tube, he will fail to raise water when the bulb is released.

110 The operation of the device illustrated in Figure 2 is slightly different.

It has been noted that the tube 13 is greatly reduced at its lower end, as indicated at 17. When the bulb 16 is squeezed, if there is water in the radiator, the bulb 5 will be slow in recovering its normal shape. If, however, the water has fallen below the predetermined level when the bulb 16 is squeezed, air will be quickly sucked into the tube and the bulb 16 will very quickly 10 cover its normal shape. With this form of device, the operator relies upon the rapidity of the recovery of the bulb as disclosed by the sense of touch or the sense of sight to ascertain whether or not the water in the 15 radiator has fallen below the danger line.

It is to be noted that the details of construction which I have illustrated show merely two of the preferred embodiments of the invention and that a great many slight 20 changes and variations might be resorted to in the construction of the tube supporting means and the bulb actuating means without departing from the invention and hence I do not wish to limit myself to the precise 25 details set forth, but shall consider myself at liberty to make such slight changes and alterations as fairly fall within the spirit and scope of the appended claims.

I claim:

30 1. The combination with a container and cover, of a frame mounted on the cover, a transparent tube extending through the frame and into the container, said frame adapted to expose a portion of said tube, 35 means for inducing a partial vacuum in the tube, and a perforated housing carried by the frame to enclose the said vacuum inducing means.

2. The combination with a container and 40 cover, of a transparent tube extending through the cover and into the container, means for inducing a partial vacuum in the tube, a protecting frame carried by the cover and enclosing the tube and vacuum inducing means, said frame being provided with 45 openings adjacent to the vacuum inducing means whereby the same may be operated.

3. The combination with a container and 50 cover, of a frame mounted on the cover, a transparent tube extending through the frame and into the container, said frame adapted to expose a portion of said tube, and means for inducing a partial vacuum in 55 the tube, said exposed portion of the tube having a caption displayed therein adapted to be magnified by the presence of a transparent fluid in the tube.

4. The combination with a container and 60 a cap having an opening therein, of a frame having a hollow threaded nipple extending through the opening of the cap, a second frame having openings therein and carried by the first frame, a bulb in the second frame, a glass tube carried by the bulb and 65 extending through the nipple into the con-

tainer, and an apertured sleeve screwed onto the nipple and surrounding the tube within the radiator.

5. The combination with a container and a cap having an opening therein, of a frame 70 having a hollow nipple extending through the opening of the cap, a second frame carried by the first frame and having openings therein, a bulb in the second frame, a tube extending from the bulb through the nipple 75 into the container, and means for securing the nipple in the opening of the cap.

6. In a device of the character described, a supporting frame including a ring provided with diametrically opposed apertures, 80 a hollow cap mounted on the ring and covering one of said apertures, said ring being provided with an annular shoulder adjacent to said aperture, vacuum inducing means mounted on said shoulder and a tube carried 85 by said means and extending from the cap and through the apertures in the ring, said cap being provided with apertures whereby to manipulate said vacuum inducing means.

7. In a device of the character described, 90 a frame including a ring provided with a plurality of apertures, an annular shoulder adjacent to one of said apertures, vacuum inducing means mounted on the shoulder, a tube carried by said means and extending 95 through the apertures in the ring, said frame also including a cap mounted on the ring and enclosing the shoulder and means carried by the cap to engage said vacuum inducing means to retain the same in operative position on said shoulder, said cap being apertured whereby to manipulate said vacuum inducing means.

8. The combination with a container and 100 container cover, a tube open at its lower end extending through the cap into the container, a bulb communicating with the outer end of the tube, a protecting and supporting frame located on the outside of the cover and carried by the cover, said frame enclosing the outer end of the tube and said bulb and exposing a portion of said bulb.

9. The combination with a container and cover therefor, of a tube carried by the cover and extending into the container, said tube 115 being provided with a flange adjacent to its upper end, a bulb carried by the tube and engaging the flange and a supporting frame carried by the cover, said frame being provided with a recess, and an annular shoulder to engage the end of the bulb and the flange respectively.

10. A gauge of the character described, comprising a frame including an apertured casing and having a hollow threaded nipple, 125 a bulb in the said casing, a tube extending from the bulb through the nipple, and a perforated sleeve surrounding the tube and screwing on the nipple.

LEONARD FOOTE.
